SUPERHEATER FOR WATER-TUBE BOILERS.

1,073,934.

Specification of Letters Patent. Patented Sept. 23, 1913.

Application filed February 7, 1910. Serial No. 542,595.

To all whom it may concern:

Be it known that we, WILHELM SCHMIDT and PETER THOMSEN, subjects of the King of Prussia, Emperor of Germany, residing at Wilhelmshöhe, near Cassel, Germany, have invented certain new and useful Improvements in Superheaters for Water-Tube Boilers, of which the following is a specification.

10 Our invention relates to water tube boilers and particularly to such boilers as are adapted for marine work. In such work many difficulties present themselves when attempting an efficient, economical and durable arrangement of parts owing to the limited space which is necessarily available, to the excessive strain and jars to which the parts are subjected and to many other conditions well known to engineers practising in this art.

15 In vessels intended for naval purposes as for example battle ships, cruisers, torpedo boats, etc., where the maximum amount of power and machinery must be installed in a minimum space, the difficulties aforesaid are greatly increased. In avoiding the difficulties peculiar to marine work, care must be taken at the same time that the requirements necessary in good superheater practice generally, shall not be disregarded or

20 slightly.

It is the object of our invention to provide an arrangement of superheater and water tube boiler, which shall be adapted to vessels of any size and in which the very special requirements pertaining to marine practice shall be met without in any way departing from the broad principles and requirements usual in stationary practice.

The nature of our present invention and its distinguishing characteristics will be understood by reference to the description following and the drawings accompanying, in which—

Figure 1 represents a section through a preferred form of our invention; and Fig. 2 a similar section through a modified form thereof.

The general arrangement both in Figs. 1 and 2 is that of a suitable superheater placed within a suitable flue, said flue being controlled by a damper and placed in parallel with another flue, whereby all or a certain proportion of the fire gases may or may not,

as is desired, pass through said superheater flue.

Referring to Fig. 1, this represents a desirable construction for general marine practice. Here a central drum E is arranged symmetrically above a pair of grates R and auxiliary drums F. These auxiliary drums F are connected to the main drum E by a central and two lateral sets of water tubes. The central set of tubes is grouped in such a way that on each side there is formed a flue A A' bounded by walls a b of water tubes placed close together and having openings at top and bottom for the entrance and egress of fire gases. Each lateral group of water tubes is arranged to have in each set thereof two flues B B' and D D'; these flues are also bounded by water tube walls c d, e f. Between B B' and D D' is a generous space in which is placed a suitable superheater u.

At the lower end of each superheater u is a damper k shown closed at the right hand side of Fig. 1 and in open position at the left hand side of the same figure. A similar damper l may be used at the upper end of the superheater if desired. Such a damper is shown at the right hand side of Fig. 1, but omitted at the left hand side.

The operation of the superheater is as follows: When steam is first to be started up, damper k (and l, if the same be used) is closed. Fire gases then pass upwardly through flue A A' over the top of walls b and c through flue B B' and up and out by way of flue D D'. As soon as the superheater u has in this way received an initial charge of steam, the dampers K (and L, if used), may be opened. This results besides opening flue C C' in closing off to a great extent, the lower end of flue B B' so that the fire gases formerly all descending said flue B B' will now, in large measure, pass across said flue at its top and down through the elements of superheater u, passing up and out as before through flue D D'.

It will be seen that by the aid of dampers K and L any desired adjustment of the distribution of fire gases as to the superheater proper and its adjacent flues, may be determined. Owing to the water tubes inclosed in flue A A', the fire gases are sufficiently cooled before they reach the said chambers

k and *l* and the superheater guarded by them, to avoid burning out and excessive wear. When it is necessary to force the boiler, the temperature of the fire gases rises 5 of course, but so does also the steam supply in about the same proportion; for this reason the liability to burn-outs and excessive wear of parts is no greater under conditions of forced supply than when the supply is 10 normal.

Fig. 2 shows a modification of the invention just described, in which two central flues *A A'* are omitted so that the fire gases reach flues *B B'* without any previous cooling. The dampers *k* and *l* also are pivoted on opposite sides from the position had by them in Fig. 1. As a consequence of this modified arrangement the fire gases may reach the superheater at a somewhat higher 20 temperature than is the case with the arrangement shown in Fig. 1. It will be noted further that the gases instead of dividing between flues *B B'* and *C C'* and then passing off through the single flue *D D'* as in 25 Fig. 1 will now pass downwardly through the single flue *B B'* and divide upwardly between the flues *C C'* and *D D'*.

The flue walls *a*, *b*, *c*, *d*, etc., are preferably, as has been described above, of water 30 tubes arranged in wall formation with ends suitably separated at top and bottom to allow the fire gases to pass. Such an arrangement of water tubes to constitute walls is now fairly well known. Instead of using 35 water tubes for such flue walls, however, we may, if we desire, constitute them of fire brick, asbestos or any other equivalent material, without departing from the spirit of our invention.

Many modifications in detail of the invention herein described may be made, and in showing only two arrangements we do not by any means wish to limit ourselves to such, but wish it to be understood that all variations of said described structure are considered by us as part of our invention so long as they are described by the claims appended hereto. An advantage of our improved arrangement of superheater as herein set forth is that the water tubes employed 50 may be the usual small tube which would be employed for the water tube boiler without superheater. While we prefer such usual tubes, we may, if desired, use tubes of larger 55 size without departing from the spirit of our invention.

We claim as our invention:

1. In a water tube boiler comprising upper and lower drums connected by sets of 60 water tubes each of which sets is arranged to provide a plurality of flues, a set of said tubes

having some tubes bent away from others so as to provide a special flue adapted to be paralleled with an adjacent flue of the same set, a superheater within said special flue, 65 and a regulating damper at an end of said parallel flues.

2. In a water tube boiler comprising upper and lower drums connected by sets of water tubes each of which sets is arranged 70 to provide a plurality of flues, a set of said tubes having some tubes bent away from others so as to provide a special flue adapted to be paralleled with an adjacent flue of the same set, a superheater within said special flue, 75 and a regulating damper at an end of said parallel flues, the area of said damper corresponding to the section of the special flue and being less than that of the aforesaid adjacent flue. 80

3. In a water tube boiler comprising upper and lower drums connected by sets of water tubes, each of which sets is arranged to provide a plurality of flues, a set of said tubes having some tubes bent away from others so as to provide a special flue adapted 85 to be paralleled with an adjacent flue of the same set, a superheater within said special flue and a regulating damper at an end of said parallel flues, said damper being arranged to completely shut off the superheater flue when in one of its limiting positions and to incompletely shut off the aforesaid adjacent flue when in the other of its limiting positions. 95

4. In a water tube boiler comprising upper and lower drums connected by sets of water tubes arranged to form three serially disposed flues, the arrangement of the water tubes so as to constitute a central flue such 100 that some tubes are bent away from others to provide a special flue in parallel with an adjacent flue also formed out of the central flue, a superheater within said special flue, and a damper at an end of said central flue 105 for regulating the relative amounts of fire gases which shall pass through the two sections of the central flue, said damper being arranged to completely shut off the special flue when in one of its limiting positions 110 and to incompletely shut off the aforesaid adjacent flue belonging to the central flue when in its other limiting position.

In testimony whereof we have hereunto set our hands in the presence of two sub- 115 scribing witnesses.

WILHELM SCHMIDT.
PETER THOMSEN.
